UNITED STATES PATENT OFFICE.

RURIC E. COBB, OF LONGWOOD, FLORIDA.

MOUTHPIECE.

Application filed May 22, 1924. Serial No. 715,206.

To all whom it may concern:

Be it known that I, RURIC E. COBB, a citizen of the United States, residing at Longwood, in the county of Seminole and State of Florida, have invented certain new and useful Improvements in Mouthpieces, of which the following is a specification.

This invention relates to mouth pieces adapted to be used upon brass wind instruments and it consists in the novel features hereinafter described and claimed.

An object of the invention is to provide a mouth piece which makes it possible for the performer upon a wind instrument, to play the notes in the upper register easily, without the usual amount of muscular effort and excessive pressure upon the lips.

This result is obtained in general by providing means for shallowing the air chamber or cup of the mouth piece to produce the higher note and thereby shortening the vibrations of the column of air, and at the same time adjusting the tube length and preventing the tones or notes from being sharpened or raised in pitch.

With the above objects in view, the structure includes a base collar, which is slidably mounted upon a shank inserted in the tube of the instrument, and which carries a shell having a rim member inserted in the outer end thereof. A cup is slidably mounted in the rim member and is provided with a sleeve which enters the shank, means being provided for simultaneously moving the cup and the base collar longitudinally of the shank, and in the opposite directions. A spring is interposed between the shank and the rim member, and serves to hold the rim member spaced from the end of the shank.

In the accompanying drawing:

Figure 1 is an end view of the mouth piece.

Figure 2 is a side elevation of the same, partly in section, and cut on the line 2—2 of Figure 1.

Figure 3 is a fragmentary vertical sectional view of the mouth piece, cut on the line 3—3 of Figure 2.

As shown in the accompanying drawing, the mouth piece tube of the wind instrument is indicated at 1, and the said mouth piece tube is provided at its end with a flange 2. A base collar 3 is slidably mounted upon the mouth piece tube 1, and carries a cylindrical shell 4. A rim member 5 is attached to the end of the shell 4, and is inserted in the said

shell. A spring 6 is interposed between the flange 2 and rim member 5 and is coiled around the inner portion of the rim member. A cup member 7 is slidably mounted in the rim member 5, and is provided with a tube 8, which is slidably received in the mouth piece tube 1 of the instrument. Gear wheels 9 are journaled in the flange 2 and rack arms 10 are carried by the cup 7 and mesh with the teeth of the gear wheels 9 at one side thereof. Rack arms 11 are carried by the base collar 3, and mesh with the teeth of the gear wheels 9 at the opposite sides thereof, from the points at which the rack arms 10 engage the said wheels 9.

When using the mouth piece, the performer produces the lower tones in the usual way, and as he ascends the scale pressure is exerted by the hand holding the instrument, thus pressing the rim against the lip. The pressure thus exerted on the rim acts to turn through the shell and base, the gear wheels which are journalled in the flange of the shank and the rack arms 10 and 11 are moved simultaneously in opposite directions, and thus the cup is moved with relation to the rim member and the mouth piece tube and the rim member is moved with relation to the cup and tube 1. When pressure is removed, the spring 6 returns the rim member and the cup to their normal positions. It thus will be seen that any movement of the rim member in one direction actuates or moves the cup in an opposite direction, and pressure exerted to produce high tones in the instrument causes the cup to move, thus providing a more shallow air chamber between the lips of the performer and the bottom of the cup. This shortens the column of vibrating air and produces a higher tone with ease, and without the exercise of excessive pressure. At the same time the length of the tube of the instrument is varied, and this prevents the tone from being raised or made sharp, as would be the case if the air chamber only was shallowed.

Having described the invention, what is claimed is:

1. In a mouth piece, a tubular member, gear wheels journaled on the tubular member, a base collar slidably mounted upon the tubular member, a shell carried by the base collar, a rim member inserted in the shell, a spring interposed between the tubular member, and the rim member, a cup slidably mounted in the rim member and the tubular

member, and rack arms carried by the cup and the base collar and engaging the gear wheels at opposite sides thereof.

2. In combination with a tube musical instrument, a mouth piece including a rim member slidably mounted upon the tube, a compression spring holding the rim member in a predetermined position in relation to the tube, a cup slidably mounted in the rim

member and the tube, and means operatively connecting the rim member with the cup to cause the rim member and the cup to move simultaneously in opposite directions when the rim member is moved with relation to the tube. ¹⁰ ¹⁵

In testimony whereof I affix my signature.

RURIC E. COBB.
